CLAIM

The ornamental design for a hand-operated device for chopping and slicing food, as shown and described.

DESCRIPTION

FIG. 1 is a perspective view of a hand-operated device for chopping and slicing food;

FIG. 2 is a top plan view thereof;

FIG. 3 is a bottom plan view thereof;

FIG. 4 is a rear elevation view thereof;

FIG. 5 is a front elevation view thereof;

FIG. 6 is a left side elevation view thereof; and,

FIG. 7 is a right side elevation view thereof.

The broken lines depict portions of the device that form no part of the claim.

1 Claim, 7 Drawing Sheets
